GRAIN CLEANING APPARATUS

John Edward Johnson, Chicago, Ill.

Application February 28, 1930. Serial No. 432,049

6 Claims. (Cl. 209—95)

My invention relates to grain cleaners and more particularly to grain cleaners adapted to remove both the finer and larger particles from wheat grains and the like.

5 One of the objects of this invention is to provide a novel arrangement of rotary drum screens by means of which a high output capacity may be obtained upon a machine occupying relatively small space.

10 It is also a purpose of this invention to provide in a machine of this character a novel means for transporting the grain through the machine as it is being cleaned.

15 My invention also contemplates as one of its objects the provision of a novel screen element for separating the wheat from the larger grains such as oats, barley, etc.

20 Another distinct object of this invention is to provide in a system of this character novel means for maintaining the parts in proper position to continue to separate the grain even though the machine may tip from side to side as would occur if this machine were mounted on a grain thrashing device such as a combined harvester.

25 A further object of the invention is to provide in a machine of this character a novel driving means for driving the drum screens at the proper speed relative to each other.

30 Other and more particular objects and advantages of the invention will appear as the description proceeds in connection with the accompanying drawings wherein the preferred form of the device is illustrated. It is obvious, however, that various minor modifications may be 35 made from the exact details shown and described without departing from the scope of the invention as is defined by the accompanying claims.

In the drawings—

40 Fig. 1 is a longitudinal section through the machine;

Fig. 2 is a reduced side view of the machine;

Fig. 3 is an end view showing the right hand end of the machine as it stands in Fig. 2;

Fig. 4 is a section on the line 4—4 of Fig. 1;

45 Fig. 5 is a section on the line 5—5 of Fig. 1;

Fig. 6 is a horizontal section illustrating the appearance of the front end of the machine with the drums removed;

Fig. 7 is a sectional view taken centrally 50 through the machine with the screens and certain other parts left out for the sake of clearness in illustrating the driving connections for the various elements of the machine;

Fig. 8 is a detailed view partly in section of 55 one of the receiving troughs of the machine;

Fig. 9 is an end view of the left hand end of the trough shown in Fig. 8;

Figs. 10 and 11 are details of one form of screen which are used for the outer drum;

Figs. 12 and 13 illustrate the form of screen 60 used for the inner drum;

Figs. 14 and 15 illustrate a slightly different form of screen which I use alternately with the type shown in Figs. 10 and 11.

Referring now in detail to the drawings, the 65 machine consists essentially of a grain inlet 20 which is adapted, as shown more clearly in Fig. 3, to discharge the grain into the interior of an inner drum 21 which drum has an interior surface pocketed as shown by the screen illustrated 70 in Figs. 12 and 13 with a multitude of small round pockets that are of sufficient depth and size to receive and retain small seeds such as weed seeds, cockle, and broken wheat grains. This drum 21 is, as shown clearly by Fig. 1, conical in longitudinal section, gradually increasing in diameter 75 from the grain inlet end to the outlet end thereof at 22.

Thus it will be seen that if this drum is rotated 80 continuously, there will be a tendency, due to the slope of the drum, for the grain to move from right to left in the drum 21; and, as it is moving, the smaller seeds and particles will be caught in the small pockets and carried upwardly by the drum and dropped into the trough-like receptacle 23 which extends longitudinally of said drum 85 throughout substantially its entire length.

This receptacle is so mounted within the drum 21 as to normally retain itself in the position shown in Fig. 4 without rotation. It is, however, pivoted, as may be seen by an inspection of Figs. 1 and 7, by means of the tubular extension 24, the flange 25 keyed to collar 26 so as to be adjustable around the main shaft 27, and in order to hold this trough in proper adjusted position there is provided exteriorly of the main casing 90 of the machine the depending arm 28 which is fixed to the collar 26 and which carries a weight 29 so positioned as to maintain the trough 23 in proper position to receive the small particles as they drop out of the pockets in the drum 21. The weight 29 is—as shown in Fig. 3—adjustable on the arm 28 so that the position of the trough 23 may be adjusted to obtain the best results.

Within the trough 23 there is a screw conveyor 95 30 which is rotated by means of the shaft 27 so as to move the fine particles from left to right as shown in Fig. 1 and discharge them into the outlet conduit 31. The normal sized wheat grains together with the larger particles or grains such 100 105 110

as oats, barley, and short straws will of course not be picked up by the pockets in the drum 21 and will move to the left hand end of this drum where they will encounter the spiral barrier 32 which to a certain extent causes them to bank up within the drum 21 and permits their discharge only as fast as the spiral barrier 32 cuts off at each rotation a certain quantity thereof. The grain as discharged then falls into an outer drum 33 which rotates in the same direction as drum 21 but of a slightly different speed, preferably about three revolutions for four revolutions of the inner drum 21 so as to be properly loaded for its greater screening surface or the amount of grain handled in the drum 21.

Drum 33, it will be noted, also is conical in longitudinal section but is reversed end for end with respect to drum 21 so that its larger end is at the smaller end of drum 21, and its smaller end is at larger or discharge end of the drum 21. This drum 33 may be equipped with either of the type of pocket shown in Figs. 10 and 11 or that shown in Figs. 14 and 15. I prefer, however, to use that shown in Figs. 14 and 15 and to arrange the pockets so that the rows thereof extend spirally around the drum so that the longitudinal axis of the pocket lies neither in a horizontal plane nor at right angles to the axis of the drum. I find that setting the pockets diagonally with respect to the direction of rotation of the drum makes for more effective elimination of the larger particles from the wheat grains.

The drum 33 will, of course, move the grain from left to right as shown in Fig. 1 as it rotates, and, as the grain moves along, the wheat grains being shorter will drop into the pockets in the screen while the larger particles such as oats, barley, and straw cannot become lodged in these pockets and will not be carried upwardly by the drum a sufficient length to enable them to drop into the trough-like receptacle 34 which is positioned in between the two drums and which has an edge at 35 adapted to receive wheat grains as they pass upwardly past the center line of the drum 33 and tip out of the pockets on the interior of this drum.

This trough 34 has—as shown best by Figs. 1, 8, and 9—a hood 36 at the left hand end as shown in Fig. 1 which receives any grains that are picked up by the pockets at this end of the drum 33 and returns it back to this drum in order to prevent the grain from getting down into the driving mechanism or tending to clog the outlet of drum 21. Throughout the rest of its length, however, trough 35 will receive the wheat grains picked up by the drum 33 as the grains move from left to right in this drum so that by the time the right hand end of drum 33 is reached substantially all of the wheat grains will be removed and only the larger particles will remain in the outer drum. These larger particles pass over the spiral barrier 37 and are discharged into the outlet conduit 38. The wheat grains in the meantime are moved along from left to right in the trough 34 by means of a novel conveyor consisting of a spiral strip 39 wound on edge about the supporting rods 40 which are carried on the end frames of the drum 21 so as to rotate therewith. The grain moved by the strip 39 in this fashion is discharged as clean wheat through the outlet conduit 41.

In order to maintain the interior of the drums clean, I preferably provide rotary brushes such as 42 and 43 carried by the troughs 23 and 34,

respectively, and driven by means of sprocket chains 44 and 45 from the drum rotating mechanism so as to rotate in a direction to sweep the inner surfaces of the drums as they pass over the brushes. The shafts for these brushes are mounted in suitable oilless bearings such as indicated at 46 and 47 so that they require no oiling or outside attention. The drums are covered by means of a housing consisting of the end pieces 48 and 49, top section 50, and bottom section 51 which sections are supported by the main frame and the supporting legs such as 52.

It will be noted that the drum 21 is secured at one end to the annular ring 53 and at the other end to a spider 54 which in turn is carried by the collar 55 that is keyed to the main shaft 27. Ring 53 is supported by means of track 56 on a pair of rollers such as indicated at 57 and 58 which rollers are mounted on a bracket 59 carried by the end piece 49. The outer drum is supported by means of suitable rollers 60 and 61 which are carried by suitable brackets such as indicated at 62 in Fig. 1 consisting of a pair of semi-annular rings mounted on the casing member 51. Suitable track such as 63 carried by the drum 33 cooperates with the rollers 60 and 61 for this purpose. At the opposite end of the drum 33, the end piece 64 thereof is secured to a flange 65 carried by the sleeve 66 rotatably mounted by means of suitable roller bearings such as indicated by 67 upon the main drive shaft 27. This sleeve 66 carried at its outer end a sprocket wheel 68 which connects, by means of the sprocket chain 69 to an auxiliary shaft 70 driving by means of the sprocket chain 71 and sprocket 110 wheel 72, the main shaft 27 at a speed which will give the outer drum a somewhat lower speed than the inner drum, namely about three revolutions of the outer drum to four revolutions of the main shaft 27 and the inner drum. 115

Power is applied to the sleeve 66 from a motor or other suitable power device by means of the shaft 73 entering a gear housing 74 at the side and having a worm 75 which engages a worm gear 76 keyed to the sleeve 66. The housing 74 is, as clearly shown in Fig. 7, supported by means of the angle iron 77 at the end of the outer casing remote from the inlet 20.

Referring now to the screen shown in Figs. 10 and 11, this screen when used makes up the outer drum and is so mounted as to extend around the outer drum in the direction shown by the arrow in Fig. 11 so that when it is rotated the pockets at 78 have their advancing edges sloped as indicated at 79 and have a rounded grain receiving portion at 80 in which a grain of wheat such as indicated at 81 may rest. The length of these pockets is such as to exclude the longer grains such as barley and oats from falling down within the pocket, and in this way they serve effectively to separate out the wheat grains from the longer particles.

The screen shown in Figs. 14 and 15 may be arranged so that the longitudinal axis of the pockets 82 will extend directly around the drum 140 although it is preferable to arrange them with the axis on a spiral as has been hereinbefore mentioned, preferably at about 45 degrees. I find that by arranging these elongated pockets in such fashion it is practically impossible for the long grains to become lodged therein even if one end of the long grains happens to fall in the pockets as it will roll out before the pocket moves very far upwardly as the drum rotates. However, a wheat grain, due to the fact that it 150

falls completely down into the pocket will not be tipped out in any such fashion and will be carried up by the drum until it is on a line with the horizontal axis of the drum so that when it tips 5 out it will fall into the trough 34.

I have already described the manner in which the inner trough 23 is adjusted by means of the weight 29, and I also provide a similar means whereby the outer drum is automatically retained in horizontal position even though the machine itself may not be set level. This is accomplished by means of a weight 83 carried on the ring 84 which serves to support the right hand end of the trough 34, this ring 84 being supported 10 in turn by track 85 riding on rollers 86 and 87 which are also carried by bracket 59. The weight 83 will, of course, tend to bring the trough 34 into the same position at all times irrespective of whether the machine is level or not. This 15 weight is preferably slotted as shown at 88 and is secured to the ring 84 by means of suitable adjusting bolts so that its position may be changed to obtain the most efficient setting for the trough 34.

From the above description it is thought that the construction and operation of this machine 20 will be clear to those skilled in this art and the advantages thereof readily apparent.

Having thus described my invention, what I 25 claim as new and desire to secure by Letters Patent is:

1. In a grain cleaner, a grain inlet, a conical drum receiving the grain from said inlet and having means for removing the fine seeds and broken 30 grains from the whole wheat grains, a trough like receptacle within said drum receiving the fine seeds and broken grains, an outer conical drum enclosing said first named drum and inverted end for end with respect thereto, said 35 outer drum receiving the grain directly from said inner drum after it has traversed the inner drum, a trough like receptacle intermediate said drums, said outer drum having means for separating the whole wheat grains from larger particles such 40 as oats and short straws and depositing them in 45 said receptacle.

2. A grain cleaner having an inner rotatable conical drum separator, an inlet spout delivering grain directly to the small end of said inner drum, an outer rotatable drum separator receiving grain from said inner drum, and grain receiving troughs within said separators the inner 50 trough being pivoted on its longitudinal axis and having an extension beyond the grain receiving end of the inner drum, and a stationary outlet 55 spout for said trough provided with a sleeve in which said trough extension is pivoted.

3. A grain cleaner having an inner rotatable

drum separator, feeding means for supplying the grain to be cleaned to the small end thereof, an outer rotatable drum screen receiving oversize material directly from said inner drum, said drum separators being nested and conical, and the large end of said inner drum being at the small end of the outer drum, a stationary grain receiving trough between said drums, a stationary trough directly receiving screened material from the inner drum, and means rotating with said inner drum for moving the grain toward one end of said first named trough, said means comprising a spiral strip wound about the inner drum structure.

4. A grain cleaner comprising a pair of rotat- 90 ing conical drum separators nested one inside the other with their ends relatively reversed, a grain inlet to the small end of the inner one of said separators, means for moving the grain from the inlet toward the other end of said inner separator and discharging it directly into the other separator, a stationary trough directly receiving screened material from the inner separator, and said other separator being adapted to move the grain back to the inlet end of the cleaner. 95

5. A grain cleaner comprising a pair of conical drum separators nested one inside the other with their ends relatively reversed, a grain inlet to the small end of the inner one of said separators, means for moving the grain from the inlet toward 100 the other end of said inner separator, and dis- charging it into the other separator, a stationary trough directly receiving screened material from the inner separator, and said other separator being adapted to move the grain back to the inlet end of the cleaner. 105

6. A grain cleaner having outer and inner con- 110 ical nested drum separators concentrically mounted about a common axis with their ends relatively reversed, feed means feeding into the smaller end of the inner drum, a stationary trough directly receiving screened material from the inner drum, said inner drum discharging the oversize material directly into the outer drum, a main shaft fixed to the inner drum, a sleeve rotatable on said main shaft, and connected to a power source, said outer drum being rotatable on 120 said main shaft, driving means including an auxiliary shaft for driving said outer drum from said sleeve, and means connecting said main shaft with said auxiliary shaft for rotating said inner drum at a different speed to that of the outer 125 drum. 130
